UNITED STATES PATENT OFFICE.

ALEXANDER BENJAMIN KOKERNOT, OF NEW ORLEANS, LOUISIANA.

REFRIGERATOR FOR BEER-BARRELS.

SPECIFICATION forming part of Letters Patent No. 500,011, dated June 20, 1893.

Application filed August 4, 1892. Serial No. 442,149. (No model.)

To all whom it may concern:

Be it known that I, ALEXANDER BENJAMIN KOKERNOT, residing at New Orleans, in the parish of Orleans and State of Louisiana, have 5 invented certain new and useful Improvements in Refrigerator-Boxes for Beer-Barrels; and I do hereby declare that the following is a full, clear, and exact description of the same, reference being had to the annexed drawings, 10 making a part of this specification, and to the figures of reference marked thereon.

This invention relates to refrigerator boxes for beer barrels, the object being to provide a suitable stand with a refrigerating chamber 15 to receive a beer barrel and with convenient means for receiving the surplus water from a refrigerator tube in the barrel.

The invention consists in the construction and combination of devices hereinafter described and claimed.

In the annexed drawings, Figure 1 is a front view of the refrigerator box with the doors open, showing the barrel or vessel in position therein. Fig. 2 is a similar view with the 25 doors closed. Fig. 3 is a central vertical sectional view of the barrel or vessel showing the refrigerator tube in place.

In order that the contents of the barrel or vessel 1, may be more rapidly cooled, may re- 30 main cold a longer time, and to economize the refrigerating material, causing it to last longer and do greater service, I provide a cold air refrigerator box 2, the back, sides and bottom whereof are made stationary and 35 tightly jointed or fastened together; the said refrigerator box 2, being supported upon suitable legs or standards 3.

Secured to the interior of the vertical sides of the cold-air refrigerator box 2, are cleats 4. 40 A cover 5, is provided at the top of said box, which cover may be of any desired construction and secured to the box in any suitable manner, and is preferably made to fit into a rabbet in the top of the box as shown in the 45 drawings. The bottom of the box at a point below the refrigerator tube is provided with an opening which may be closed by a tight fitting cover 6, opening inward. The front of the box 2 is closed by two or more doors as 50 shown in the drawings, suitably secured to the body of the box, and having a suitable fastening device. A small semicircular portion

may be removed from each door to provide an opening through which the faucet may extend. When three doors are used I prefer to 55 so arrange them that one of said doors will cover the space from the cleats 4 to the bottom of the box, and the other doors cover the portion from said cleats to the top of the box, but it is obvious this arrangement of doors 60 may be changed at will. The interior of the box together with the inner face of the doors may be lined with any suitable non-conducting material.

To strengthen the head of the barrel, prevent it warping and to cause the packing to fit tight and snug around the refrigerator tube 7, I provide exteriorly threaded bushings 8, each provided at its outer end with a lateral flange countersunk into the barrel or vessel 70 head. These bushings receive the ends of the refrigerator tube 8. The inner end of these bushings 8 extend sufficiently inside the barrel head to receive each a ring 9, which is screwed thereupon and rests tightly against 75 the inner surface of the barrel head thereby securing the bushings 8 in position. I prefer to provide these rings with radial arms 10, which afford a means for screwing the same on the bushing and which extend almost 80 entirely across the inner surface of the barrel head, thus increasing the security of the means for retaining the bushings 8, in place. If desired I may make the exterior of the bushings 8, smooth to a short distance of their 85 inner ends and reduce and screw thread the ends thereof, in which case they may then be driven in the hole and the rings 9 screwed upon their ends. Packing material may be interposed around the bushings 8 between 90 the rings 9 and the barrel or vessel heads. The ends of the refrigerator tube 7 extend outward beyond the bushings 8, and are screw threaded exteriorly to receive flanged nuts 11. The edge of the interior circumference of each 95 bushing 8, is sunken or chamfered and the adjacent portions of the juts 11 are correspondingly sunken or chamfered whereby receptacles are formed for a packing material, thus forming perfectly tight joints when the parts 100 are in position. The end of the refrigerator tube 7 may be provided with flanged caps 11^a having smooth exteriors and screw threaded interiors.

For the purpose of providing a convenient means for receiving the surplus water discharged from the refrigerator tube, the legs which support the refrigerator box 2 are connected by horizontal bars 12, which support at their crossing portions a piece or platform 13 to support a bucket or other receptacle 13^a immediately under the door 6 in the bottom of the refrigerator box 2 and when said bucket 10 is filled it can be emptied and replaced. In place of the door 6, or in addition thereto the opening in the bottom may be closed by a supplemental receptacle 13^b provided with a flange to be engaged by turn buttons 14 secured to the bottom of the box 2 or said receptacle may be, and preferably is, integrally attached to the bottom of the box. The lower end of this receptacle 13^b is provided with a faucet 14^a. The lower end of the tube 7 is 15 screw-threaded interiorly to receive a partition 8^a screw-threaded on its exterior and provided with a faucet which is opened when it is desired to discharge the accumulated water.

To increase the ice-holding capacity of the 20 refrigerator-tube 7, and in order to obtain the best results, a flanged, cylindrical, supplemental joint 15 is closely fitted in the top hole of the refrigerator box, its flange fitting a recess in the top of said box and its lower end 25 fitting snugly in the top end of the refrigerator tube.

To put the refrigerator box in operation, its top front doors are opened and the barrel or vessel with the faucet and the refrigerator tube attached and packed with ice, is placed 30 in the refrigerator box, the bottom of the barrel or vessel resting on the cleats 4, and the doors of the refrigerator box are then closed. No cover is required for the refrigerator tube 35 in the vessel in the refrigerator box. The re-

frigerator tube is supplied with ice through the cover 5 at the top of the box, as required, and whenever it is required to discharge the surplus water in the refrigerator tube the faucet in the lower bushing 8, is opened as is 45 also the door 6 in the bottom of the refrigerator box, so that the water will flow into the bucket or vessel 13^a. When, however, the supplemental receptacle 13^b is employed, the faucet in the partition 8^a may be allowed to 50 remain open when the surplus from the refrigerator tube will drip into the receptacle 13^b and may be discharged therefrom through the faucet 14^a.

What I claim as my invention is—

1. The combination with a refrigerator box having legs and provided with cleats for supporting a beer barrel within said box, said box provided with an opening in its lower end, of a receptacle detachably connected 60 with said opening and provided with a faucet to receive and draw off the drip from the refrigerator tube in the barrel, substantially as described.

2. The combination with a refrigerator box 65 having an opening in its top, and a barrel or vessel supported in said box and provided with a vertically arranged refrigerator tube, of a detachable supplemental joint for connecting the upper end of said tube with the 70 opening in the top of the box, substantially as described.

In testimony whereof I have hereunto subscribed my name in the presence of two witnesses.

ALEXANDER BENJAMIN KOKERNOT.
